Primary Examiner — Marissa J Cash(74) *Attorney, Agent, or Firm* — Davis & Bujold PLLC;
Michael J. Bujold(57) **CLAIM**

I claim the ornamental design for an aircraft with multiple rotors, as shown and described.

DESCRIPTION

FIG. 1 is a top, front, right perspective view of a aircraft with multiple rotors embodying my/our new design;

FIG. 2 is a front elevational view thereof;

FIG. 3 is a rear elevational view thereof;

FIG. 4 is a right side elevational view thereof;

FIG. 5 is a left elevational view thereof;

FIG. 6 is a top plan view thereof; and,

FIG. 7 is a bottom plan view thereof.

The broken lines illustrate environmental structure that form no part of the claimed designed.

1 Claim, 7 Drawing Sheets(56)
